CLAIM

The ornamental design for a battery handle assembly tab, as shown and described.

DESCRIPTION

FIG. 1 is a front perspective view of a battery handle assembly tab showing our new design, according to a first embodiment;

FIG. 2 is a front elevational view thereof;

FIG. 3 is a rear elevational view thereof;

FIG. 4 is a right side elevation view thereof, the left side elevation view being a mirror image;

FIG. 5 is a top plan view thereof, the bottom plan view being a mirror image;

FIG. 6 rear perspective view thereof;

FIG. 7 is a front perspective view of a battery handle assembly tab, according to a second embodiment;

FIG. 8 is a front elevational view of the battery handle assembly tab of FIG. 7;

FIG. 9 is a rear elevational view of the battery handle assembly tab of FIG. 7;

FIG. 10 is a right side elevational view of the battery handle assembly tab of FIG. 7, the left side being a mirror image;

FIG. 11 is a top plan view of the battery handle assembly tab of FIG. 7, the bottom plan view being a mirror image; and,

FIG. 12 is a rear perspective view of the battery handle assembly tab of FIG. 7.

The broken lines in the drawings are for the purpose of illustrating portions of the battery handle assembly tab that form no part of the claimed design.
